UNITED STATES PATENT OFFICE

2,640,107

TELEPHONE PAY STATION CIRCUIT

Clarence E. Lomax, Chicago, and Ray John Gallagher, River Forest, Ill., assignors to Automatic Electric Laboratories, Inc., Chicago, Ill., a corporation of Delaware

Application April 13, 1951, Serial No. 220,778

3 Claims. (Cl. 179—6.3)

1

This invention relates in general to telephone paystation circuits and more particularly to such circuits including a device for controlling the availability of the coin channel for the acceptance or non-acceptance of deposited coins.

The main object of this invention is to provide a simple circuit modification to present existing, as well as new, paystations that will allow a mechanical device to reject a certain denomination coin (a nickel in the present illustration) for initiating a call; whereas once a call has been initiated with a coin of another denomination (a dime or quarter in the present illustration) that previously rejected denomination coin will then be acceptable for toll calls.

Other objects of the invention will appear upon a further perusal of the specification taken in conjunction with the accompanying drawings, in which Fig. 1, which illustrates diagrammatically the apparatus and circuits involved in a system employing the invention. Fig. 2 is a rear view of the upper part of a paystation telephone with the back board removed. Fig. 3 is a detailed sectional view of the nickel channel taken along the line 3—3 of Fig. 2. Fig. 4 is a top sectional view of the coin channels in the coin chute and of the controlling mechanism taken along the line 4—4 of Fig. 2.

Reference may be had to co-pending application of Ray John Gallagher, Serial No. 169,479, filed June 21, 1950, wherein there is disclosed a mechanical adaptation in the paystation coin chute for rejecting an initially deposited nickel, thereby compelling the calling party to deposit a dime or quarter to effect the connection. Once the call is initiated the nickel coin channel is conditioned for subsequent acceptance of nickels in payment of toll charges. The present invention utilizes this mechanical adaptation and concerns itself with the means for controlling the said conditioning means for the nickel channel. An illustrated portion of the drawings of the above-mentioned application has been shown representing Figs. 2, 3 and 4 of the drawings in this application. Referring to Fig. 2 it will be seen that the coin chute 9 is shown as mounted within the paystation housing and being normally positioned over the coin hopper 1. Fig. 3 shows the nickel channel 4 with the flexible spring 2 in its normal or diverting position, also shown is the coin retaining walls or surfaces 5 and 6. Fig. 4 shows the nickel channels 4 of the coin chute 9 and also the control relay 10 as being mounted on the coin chute. The control relay 10 is shown in the operated position, in which

2

the operated armature 1 has engaged the spring 2 and moved it out of the normal diverting position in the nickel channel and into the accepting position. It will be seen that in this position the spring 2 combines with the wall 6 to form a complete retaining wall. A more complete description of this apparatus is covered in the above-mentioned application. In the hereinbefore cited co-pending application a portion 5 of the upper wall of the nickel channel is removed and replaced by a small rectangular thin sheet of nickel silver (controlling spring) projecting diagonally into the channel and anchored at one end to the coin chute. The other 10 end is flexed to an other than normal position by the armature of a control relay. This controlling spring is normally positioned in the nickel coin channel so that a deposited nickel will be diverted to fall out of the channel into the refund 15 chamber in the same manner as would a non-standard coin. Thus, the party would have to deposit a dime or quarter to actuate the coin trigger contacts for initiating a call. In the present invention this control relay, disclosed in the 20 hereinbefore cited co-pending application, is connected in the paystation circuit in series with the line so that it will operate once the call is initiated and a finder has found the line. The controlling spring will be flexed or pivoted 25 out of the channel responsive to the operation of this control relay; and therefore any subsequent nickels deposited for toll charges will pass through the entire nickel channel to strike the coin signal bell. The control spring forms a retaining 30 wall for the channel in the flexed position.

Referring now to the drawings a detailed description thereof will now be given. Assuming 35 that a party desires to make a local call and removes the receiver and deposits a dime. As hereinbefore mentioned, with the mechanical adaptation disclosed in the co-pending application, a deposited dime will effect the closing of coin trigger contacts 31. The coin collect-refund magnet 30 will therefore be connected to the 40 positive line and line relay 35, in the individual line circuit associated with the paystation, will operate, over the following circuit: ground, coin collect-refund magnet 30, coin trigger contacts 31, positive talking conductor 34, contacts 31, through line relay 35, to battery. Magnet 30 will not energize in this circuit. Responsive to 45 the operation of line relay 35, finder 38 is initiated to seek out the calling paystation line in well-known manner. When the line is found by 50 finder 38 and repeater 39 is connected thereto,

the line relay in the repeater will connect negative potential to negative talking conductor 33 and ground will be connected to positive talking conductor 34. Typical repeater 39 may be of the type disclosed in U. S. Patent 2,113,080, issued to T. F. Crocker et al., April 5, 1938. Responsive to this application of potential across the talking conductors, control relay 10 operates, over the following circuit: negative potential on negative talking conductor 33, through control relay 10, coin signal transmitter 13 and shunting resistor 14, talking transmitter 16, induction coil winding 18, dial pulsing contacts 22, hook switch contacts 26, to ground on positive talking conductor 34. The operation of relay 10 actuates armature 1 which in turn flexes controlling spring 2 to the accept position. The paystation is now conditioned for acceptance of nickels as is fully described in the hereinbefore cited co-pending application. The call may now be extended, responsive to dialing, in well-known manner through selector 40, and via conductors 54, 55 and 56 through connector 41 to substation 42.

For this previously described local call, the conditioning of the paystation for acceptance of nickels serves no useful function; however, assuming the party dialed the toll operator over finder 33, repeater 39, selector 40, and via conductors 51, 52 and 53 to the toll operator's position 59, this conditioning will be necessary. It is very important that the nickel channel be available for toll charges as all denomination coins will invariably be deposited. Thus, it is seen that while the nickel channel is initially blocked, once a call is initiated that nickel channel will be useful for depositing the toll charges.

A slight modification of this circuit will cause control relay 16 to be responsive only to the answering of the called party. This is effected by utilizing X wiring which places rectifier 11 in parallel with control relay 10. During switching and up until the time the called party answers negative potential will be placed on conductor 33 and rectifier 11 will shunt the loop current around control relay 10, thereby preventing it from operating. However, responsive to answering, battery is reversed over the lines in well-known manner and the negative potential will thereafter be connected to talking conductor 34. The current through the paystation will, of course, reverse and rectifier 11 will not conduct. Substantially all of the loop current will therefore pass through control relay 10 and cause operation of same. Thus it is seen that the conditioning process may be delayed until the answering operation.

It might be noted that during dialing, shunt spring contacts 24 shunt out the control relay, thereby eliminating the inductive effect therefrom. Condenser 12 is placed in parallel with control relay 10 in order to form a by-pass circuit for the audio current.

While there has been described what is at present considered to be the preferred embodiment of the invention, it will be understood that various modifications may be made therein, and it is intended to cover in the appended claims

all such modifications as fall within the true spirit and scope of the invention.

Having described our invention in detail, what we claim and desire to have protected by issuance of Letters Patent of the United States is:

1. In a telephone paystation, a transmitter, a line, a finder-repeater link for seizing said line, a coin channel having retaining surfaces leading to a hopper, a portion of one of said retaining surfaces comprising a flexibly mounted coin controlling spring, said spring and channel normally positioned so that coins will not be retained within said channel at one time, and a control relay in series with said transmitter for flexing said spring to retain coins within said channel at other times, said relay operable responsive to seizure of said line by said finder-repeater link.

2. In a telephone paystation, a line, a finder-repeater link for seizing said line, means for supplying reverse battery to said line, a transmitter, a coin channel having retaining surfaces leading to a hopper, a portion of one of said retaining surfaces comprising a flexibly mounted coin controlling spring, said spring and channel normally positioned so that coins will not be retained within said channel at one time, a control relay in series with said transmitter for flexing said spring to retain coins within said channel at other times, and a rectifying device connected in parallel with said relay, said rectifying device preventing said relay from operating upon seizure by said finder-repeater link, said relay thereafter operating responsive to the operation of said reverse battery means.

3. In a telephone paystation, a line, a coin channel, a flexible spring associated with said channel and normally projecting into said channel for diverting a deposited coin therefrom, a control relay associated with said flexible spring, said control relay included in series with said line responsive to the initiation of a call over said line by said paystation, means for supplying normal polarity of battery current to said calling line, a rectifying device connected in parallel of said control relay, said rectifying device being conductive to said normal polarity of said battery current for preventing the operation of said control relay, and means for thereafter reversing the polarity of said battery current to said calling line, said rectifying device being non-conductive to said reversed polarity of said battery current, whereby said control relay is operated by said reversed polarity for moving said flexible spring out of said normal diverting position in said channel and into a non-diverting position.

CLARENCE E. LOMAX,
RAY JOHN GALLAGHER.
